(57) **CLAIM**

The ornamental design for a halligan tool, as shown and described.

DESCRIPTION

FIG. 1 is a front elevational view of the halligan tool;

FIG. 2 is a rear elevational view thereof;

FIG. 3 is a left-side elevational view thereof;

FIG. 4 is a right-side elevational view thereof;

FIG. 5 is a top plan view thereof; and,

FIG. 6 is a bottom plan view thereof.

The broken lines in the drawings are directed to an area of the halligan tool that forms no part of the claim.
